[57] CLAIM

The ornamental design for portion of a carrying rack for positioning on top of an automobile, as shown and described.

DESCRIPTION

FIG. 1 is an end elevational view of a portion of a carrying rack for positioning on top of an automobile showing our new design;

FIG. 2 is a front elevational view thereof, the rear being a mirror image of that shown;

FIG. 3 is a bottom plan view thereof;

FIG. 4 is a top plan view thereof; and,

FIG. 5 is a perspective view thereof.
